UNITED STATES PATENT OFFICE

2,574,509

VERTICAL AXIS BEADING

Kimberly Stuart, Menasha, Wis., assignor of one-half to Elizabeth R. B. Stuart, Menasha, Wis.

Application July 31, 1946, Serial No. 637,267

6 Claims. (Cl. 153—1)

1

This invention relates to a method and apparatus for applying reinforcing rim strips to containers, closures and other articles.

It has become common practice to apply metallic rim strips to containers and other articles made of paper, pulp board, fibrous sheet material and the like to reinforce them against distortion and as an added protection and ease in handling. A special rimming machine and method used extensively for this purpose is disclosed and claimed in United States Letters Patent No. 2,283,962 to Wilson et al., and the present invention relates more particularly to improvements, variations and refinements in the apparatus and method disclosed in said patent.

The invention of the above Wilson et al. patent, and the inventions disclosed in this specification relate to high speed production of rimmed articles. Prior to these inventions the practice was usually to provide preformed metal hoops to the article edges, a procedure requiring individual fitting of each hoop to that contour of the article edge. This took time and was expensive because of the labor involved. The present inventions embody substantially continuous rimming of a series of articles in succession with no problems of fitting because the metal strips are shaped and secured to the article in a continuous operation.

It is a major object of this invention to provide a novel method and apparatus for continuously and positively forming and fastening reinforcing or sealing rims to articles of paper board, fiber board and the like from a length or reel of strip metal as contrasted with the usual pre-formed hoop.

It is a further object of the invention to provide a novel method and apparatus for fastening a rim strip to the edge of an article wherein a strip is transversely curved to provide a substantially C-shaped rim clenched about and along the edge of the article and laterally bent to follow the contour of the edge of said article.

A further object of the invention is to provide a novel method and apparatus for forming and clenching a generally C-shaped rim strip about and along the edge of an article wherein the article is supported for rotation about a generally vertical axis and a flat or preformed strip fed in a direction substantially perpendicular to that axis, the strip being bent transversely and longitudinally as it is secured to the article.

It is a further object of my invention to provide a novel method and apparatus for securing a rim strip to the edge of an article wherein a rim

2

strip is transversely curved about its longitudinal axis and bent in a direction substantially parallel to its direction of feed.

A further object of the invention is to provide a novel method and apparatus for securing a sheet metal or like rim strip along and about the edge of an article wherein the strip is subjected to preshaping prior to being clenched to said article and controlled bending of the clenched strip to follow the contour of said edge is provided.

Further objects of the invention will presently appear as the description of the invention proceeds in connection with the appended claims and the annexed drawings in which:

15 Figure 1 is a top plan view of the rimming apparatus constructed according to a preferred embodiment of my invention;

20 Figure 2 is a side elevational view of the pre-forming rollers, showing the section of the metallic rim strip as taken on line 2—2 of Figure 1;

Figure 3 is a sectional view taken on the line 3—3 of Figure 1 illustrating particularly the strip forming and clenching rolls;

25 Figure 4 is a side elevational view, partially in section, taken on line 4—4 of Figure 1 illustrating particularly the adjustable strip bending roll; and

30 Figures 5, 6 and 7 are sectional views along lines 5—5, 6—6 and 7—7 in Figure 1 illustrating the rim in successive formative stages.

Referring to Figures 1—4, the article support of the rimming machine is designated generally at 15 and comprises a substantially dish-shaped rigid article retainer member 16 within which a preformed paper or pulp receptacle, container or like article to be rimmed 17 preferably snugly engages the inner walls and bottom of member 16. This is preferable so that, when member 16 is rotated about its axis, article 17 will be carried along without any intermediate drive connection therebetween than their mutual friction.

Retainer member 16 has a depending integral bearing housing 17' within which one end of a vertical standard 18 is journaled. The lower end of standard 18 has a reduced portion 19 which is bent at a right angle to the upper enlarged portion to form an integral pivot pin 21 slidably engaged in an elongated slot 22 of a treadle lever 23. Lever 23 is provided at one end with a foot pad 24 and is pivoted at 26 in an upstanding lug formation 27 which is rigidly secured to the base of the rimming machine or upon any convenient place on the floor near the base of the machine. The opposite end of lever 23 is secured to one end of coil spring 28 anchored

near the floor as at 29, and spring 28 tends to urge lever 23 in a counterclockwise direction about its pivot at 26. The extreme end of lever 23 is pivotally connected as at 31 to a clutch operating arm 32 for a purpose to be described later. When an operator presses down with his foot on pad 24, standard 18 and member 16 will be elevated to advance the article on the latter into position to be rimmed as will appear.

In securing the reinforcing rim to the article 17, the leading end of a flat metallic strip 33, preferably of sheet steel, is inserted into a horizontally slotted guide diagrammatically illustrated at 34. Strip 33 may be a strip precut to exact length or may be fed from a reel, with a suitable automatic cutter (not shown) interposed to divide it into proper lengths. Slot 36 in the guide holds strip 33 in a horizontal plane as the strip is fed into the pass defined by preforming rollers 37 and helps to prevent askewness of the strip as it is formed and secured to article 17. When strip 33 leaves preforming rollers 37 it has acquired an open, inverted U-shaped configuration in transverse cross section as illustrated in Figure 6. As illustrated in Figures 2 and 6 the action of preforming rolls 37 is to preform strip 33 initially by imparting to it an arcuate transverse curvature about its longitudinal axis. If desired however rollers 37 could be omitted and a strip 33 factory preformed to the shape of Figure 6 provided.

Preforming rollers 37, illustrated best in Figure 2, are similar to those shown in U. S. Patent 2,281,889 issued to Allen B. Wilson and myself and comprise arcuate strip forming surfaces 38 and enlarged contacting cylindrical portions 39 mounted on shafts 41. One of the rollers 37 may be non-rotatably mounted on its shaft which is driven by any suitable means, not shown, while the other roller may be freely rotatably mounted on a stationary shaft. Shafts 41 are vertical and parallel and are so positioned that the peripheral edges of roller portions 39 are constantly in contact whereby the surfaces 38 are always maintained in the same relation.

After strip 33 has been inserted into guide member 34 and is engaged by the preforming rollers 37 it is then advanced mechanically, partly due to the frictional engagement of the strip by the strip contacting surfaces 38, and is thereby advanced into the roller pass at the rim securing station 43 which is located at a point tangential to the edge of the article upon which the strip is to be fastened.

In its operative position, rim securing means 43 functions to curl or bend partially preformed strip 33 transversely about longitudinal axis and in a direction generally parallel to the plane of the strip prior to preforming until it assumes a generally circular or C-shaped cross section to embrace the opposite sides of the vertical article edge or edges. When the strip is clenched along and about the article edge by action of rollers 44 and 45 at station 43, the lateral edges of the metal rim are caused to bite into opposite sides of the article due to the small area of contact between the relatively sharp strip edges and the relatively soft article surface and the high pressure incident to bending the strip to substantially C-shape about the article edge. The metal retains its given C-shape and remains clenched about the article edge after the operation is completed. Where the article edge to be rimmed is circular, strip 33 is preferably fed into station 43 at a tangent thereto.

Rim securing station 43, as illustrated in Figure 3, comprises a pair of rollers 44 and 45 having arcuate identical strip contacting faces 46 and 46' of desired contour and enlarged contacting cylindrical roller portions 47. Rollers 44 and 45 are non-rotatably secured to shafts 48 and 49. Shaft 49 is rotatably journaled in a supporting arm 51 which is pivotally secured by a suitable pivot assembly at 52 to arm 53. At the upper end of arm 51 shaft 49 carries a gear 54 non-rotatably mounted thereon which meshes with a gear 56 fixed to shaft 48.

Gears 54 and 56 are constantly engaged and are designed to allow pivotal movement of arm 51 about pivot 52 while the gears are rotating without causing binding of the gears. Arm 53 is provided with a rigid stop 57, and a spring 58 extends between lug 57 and a recess 59 in arm 51, in which it is engaged, tending to rotate arm 51 about its pivot 52 in a counterclockwise direction and thereby separate the forming rollers.

From the above it will be seen that roller 44 is mounted for movement toward and away from roller 45 to permit insertion of the edge of the article 17 between the rollers. To insure proper action between gears 54 and 56 during rimming operations, a cam arrangement is provided for insuring that shaft 49 is maintained parallel to shaft 48 during that period. A cam shaft 61 is connected to a driving means by a suitable gear arrangement, not shown, and is provided with a cam 62 non-rotatably mounted thereon.

Arm 51 is provided, adjacent pivot 52, with an arm 68 having a suitable pivot assembly 69 for supporting a rocker arm 71 intermediate its ends. At one end, arm 71 is provided with a freely rotatable roller 72 designed to follow the surface of cam 62. At its other end, arm 71 is bent laterally to a position along the side of arm 51 and is there formed with a threaded boss 73 through which extends an adjustable stud 74 having a suitable stop formation 76 for engaging a stop surface 77 on arm 51.

When roller 72 enters recessed portion 63 of cam 62, this permits spring 58 to force arm 51 away from arm 53 to separate rollers 44 and 45, and rim securing station 43 is now in position to receive the edge of the article to be rimmed. The article can be raised into the open roller pass by stepping on pad 24. As rim 33 is secured to the top edge of the vertical wall of the article, the driven rollers of securing station 43 frictionally cause article 17 and support 16 to rotate about the vertical axis of standard 18. At station 43, the preformed strip 33 is clenched tightly about and along the upstanding edge of article 17, the opposite lateral edges of the strip biting into the softer material of the article on opposite sides of the edge as illustrated in Figure 3. This manner and apparatus for clenching the strip to the article is preferably the same as disclosed in said Patent 2,283,962 to which attention is directed for further detail if needed. The tangential path of travel of rim strip 33 is then diverted by a suitable adjustable curling shoe assembly 78 adjacent rimming station 43, to aid in imparting a circumferential bend to the strip to urge it to conform to the contour of the container edge being rimmed.

Curling shoe 72 is provided with a tapered portion 79 which extends almost into the space between rollers 44 and 45 at the point where the strip leaves station 43, and is secured to any suitable stationary part of the machine (not shown) as by a cap screw 81 which passes through an

elongated slot 82 in projecting lug portion 83 to allow radial adjustment of the shoe to adapt it to different size rim strips. Shoe 78 is provided with an arcuate strip contacting face 89 which conforms to the peripheral contour of the vertical wall of the article 17. A groove 91 is provided in face 89 to aid in retaining the article in its holder while circumferential bending is being imparted to the rim.

To further aid in the longitudinal bending of rim 33 to follow the contour of the article edge a radially adjustable roller 92, illustrated in Figure 4, is rotatably mounted on the lower end of a vertical shaft 93 which has the other end secured in block 94 as by a pin 96. Block 94 is slidably mounted in a frame 97 having supporting ledges 98 on opposite sides thereof and set screws 97 threaded in the end walls. Frame 97 is secured to stationary arm 101 in any suitable manner, as by welding.

Roller 92 is located within the article being rimmed, and set screws 99 and shaft 93 are preferably in a radial plane of the circular article beyond the end of the forming shoe whereby adjustment of set screws 99 will slide block 94 along supporting ledges 98 to impart adjustment to roller 92 along the radius of rim 33 for moving the roller toward or away from the rim. When in its properly adjusted position, groove 95 in roller 92 engages rim 33 as shown in Figure 4.

Circumferentially beyond roller 52, a pair of rollers 102 similar to those at station 43 may be located. These rollers are mounted and operated like rollers 44 and 45 and impart the finishing transverse crimping or clenching of the rim about its longitudinal axis, and they also serve to fulcrum rim 33 about roller 92, thereby aiding controlled circumferential bending of the rim.

In operation an article to be rimmed, such as the cardboard can header 17, is placed in member 16. Strip 33, preformed to the sectional shape of Figure 6, is advanced toward the roller pass of station 43. As the strip enters the pass treadle 23 is depressed by the operator to raise member 16 until the edge to be rimmed is disposed within the roller pass. The roller passes at 43 and 102 are initially open to receive the header edge, roller 72 being disposed in cam recess 63. Preferably depression of treadle 23 causes lever 32 to operate a clutch that drives shaft 61 for a complete revolution in the manner that closing of the roller pass is accomplished in Patent 2,283,962 to which reference is made for detail if needed. During revolution of cam 62, the strip is frictionally fed through station 43 and the same time clenched about and along the freely rotating header edge. The parts and strip length are so proportioned that during one revolution of cam 62 the header edge is completely rimmed with a slight telescoping overlap at the strip ends.

The preforming step at rollers 37 may be dispensed with if desired and preformed and precut lengths of material supplied as in Patent 2,283,962. In the rimming of some large diameter articles the preforming may be entirely omitted. The strips may be fed to pass 43 manually or automatically.

Since strip 33, in order to follow the circular periphery of header 17, must bend in a direction substantially parallel to its path of movement into the roller pass, and since the material of header 17 may not be strong enough to compel such bending as the strip advances, I provide roller 92 to aid in this bending action. Shoe 78

may be dispensed with except for very stiff rim material. Actually the clenched-on rim section between station 43 and rollers 102 is effectively fulcrumed about its contact with roller 92 which may be adjusted to increase or decrease its bending action. If needed, a groove idler roller can be provided on the side opposite roller 92.

This aid to bending of the clenched rim is particularly desirable as in the present embodiment where the bending action to follow the article edge contour must take place in a direction substantially parallel to the plane of flat strip 33. In such a method, in the absence of special auxiliary forming apparatus the strip is imparted its C-shape about its longitudinal axis prior to such circumferential bending, because to bend the flat strip laterally in its plane would form wrinkles and unevenness in the inside portion thus rendering it difficult to later form into the transverse C-shape necessary to clench onto the header.

It will be appreciated that the present invention is not limited to the rimming of circular articles but may be utilized in rimming articles of any edge contour where the junctures or corners between adjacent edge portions are arcuate so as to permit a continuous operation.

The invention is not only applicable to rimming articles having single continuous edges, but may also be employed to secure together the side by edge regions of two or more separate members. It will be understood that reference to an article edge herein is therefore to be interpreted of sufficient scope to cover the securing of adjacent members together by a metal strip which extends over such side by side edges and bites into the separate members at opposite sides.

It will thus be seen that in all forms of this invention substantial transverse bending of the metallic strip is performed before any circumferential bending of the strip to approach the contour of the edge to be rimmed.

This invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for applying a stiffening rim upon a generally circular article comprising means supporting said article for free rotation with its peripheral edge adjacent a rim securing station, means for laterally prebending a strip of metal about its longitudinal axis and advancing it longitudinally toward said station in a slightly arcuate condition substantially tangentially of the peripheral edge of said article, means at said station for further bending said strip transversely of its length and about its longitudinal axis around the peripheral edge of said article with the opposite lateral edges of said strip disposed angularly with respect to the opposite sides of said article at said edge whereby the opposite lateral edges of said strip are forced into intimate locking engagement with said article, said means also being operable to rotate said article and advance said strip through said station so that said strip is progressively fastened along the peripheral edge of said member, means radially adjustable with respect to said circular article for

engaging said fastened strip beyond said rim securing station for laterally bending said strip in a direction substantially parallel to the general plane of the original strip to conform said strip substantially to the periphery of said article.

2. Apparatus for applying a rim upon a generally circular article comprising means supporting said article for free rotation with its peripheral edge adjacent a rim securing station, said rim securing station comprising cooperating arcuately faced forming rollers mounting on vertical axes, a subsequent arcuate shoe member co-operating with said forming rollers to impart lateral curvature to said rim as it emerges from said rollers, said rollers being operable to rotate said article and advance said rim through said station so that said rim is progressively fastened about and along the peripheral edge of said article, and means for adjusting said shoe substantially along a radius of said article.

3. In a method of securing a metallic strip along and about the circular edge of an article of softer material mounted for rotation about an axis wherein said strip is advanced flat in a plane substantially perpendicular to said axis, the steps of securing said strip to said edge by lateral bending about its longitudinal axis and imparting lateral curvature to said secured strip to conform to the contour of said edge as said article rotates.

4. In apparatus for applying a rim strip to an

5 10 15

edge of an article mounted for rotation about a vertical axis, means for horizontally advancing a strip toward said edge with the wide dimension of said strip disposed substantially in a horizontal plane, means for clenching said strip about and along said edge as the article rotates in response to advancement of said strip, and means acting on the portion of said strip which is clenched to said article for positively forming said strip to follow the peripheral contour of said edge.

5. In the apparatus defined in claim 4, means for preforming said strip into downwardly facing arcuate cross section prior to said clenching.

6. In the apparatus defined in claim 4, means beyond said positive forming means for finish clenching said strip about said edge.

KIMBERLY STUART.
